US00D851400S

(12) **United States Design Patent** (10) **Patent No.:** **US D851,400 S**
(45) **Date of Patent:** **** Jun. 18, 2019**

(54) **DUFFEL BAG**

(71) Applicant: **YETI Coolers, LLC**, Austin, TX (US)

(72) Inventors: **Roy Joseph Seiders**, Austin, TX (US);
Erik Steven Larson, Austin, TX (US);
Derek G. Sullivan, Austin, TX (US);
Alex Baires, Austin, TX (US); **Jeffrey Charles Munie**, Austin, TX (US)

(73) Assignee: **YETI Coolers, LLC**, Austin, TX (US)

(**) Term: **15 Years**

(21) Appl. No.: **29/639,767**

(22) Filed: **Mar. 8, 2018**

(51) **LOC (11) Cl. 03-01**

(52) **U.S. Cl.**

USPC **D3/289**

(58) **Field of Classification Search**

CLAIM

The ornamental design for a duffel bag, as shown and described.

DESCRIPTION

FIG. 1 is a top, front, right perspective view of a duffel bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate stitching and the zipper teeth. None of the broken lines form part of the claimed design.

1 Claim, 6 Drawing Sheets

US D851,400 S
